UNITED STATES PATENT OFFICE

WILHELM FISCHER, OF AKRON, OHIO

AIR-COOLED ENGINE FOR AIRCRAFT

Application filed September 18, 1929. Serial No. 392,828.

This invention relates to internal combustion engines, and it has particular relation to a device for facilitating the circulation of air about the cylinders of air-cooled engines of 5 aircraft or other propelled vehicles.

The principal object of the invention is to reduce the air resistance of the cylinders of air-cooled engines.

Another object of the invention is to improve 10 the cooling of the leeward portions of the cylinders of air-cooled engines.

Another object of the invention is to improve carburetion of the fuel in air-cooled internal combustion engines.

15 Inasmuch as air-cooled internal combustion engines must be exposed to an air stream in order to effect the necessary dissipation of heat, they cause considerable air resistance which should be maintained at a minimum.

20 Stream-line cowlings have been disposed about such engines for the purpose of reducing the air resistance thereof. However, these cowlings must leave the finned cylinder barrels of the engine uncovered and exposed 25 to an air stream of high velocity in order to secure the necessary dissipation of heat.

Experiments conducted in a wind tunnel, wherein a cylindrical body was so exposed to the air stream that the principal axis of 30 the body was disposed at right angles to the air stream, have shown that the air resistance can be materially reduced by employing a suction producing means to draw air from the boundary layer of the body. By employing 35 a suction producing means in this manner the air is directed closely along the circular contour of the cylindrical body, thereby decreasing the eddies and in consequence, reducing the air resistance of the body.

40 According to this invention, which is based upon these experiments, the air is drawn by suction away from the leeward portions of cylinder barrels of an air-cooled engine for the purpose of decreasing the air resistance 45 of the cylinder barrels and to improve the air cooling of the leeward portions of the barrels.

Another important feature of my invention is to utilize, for the purpose described above, 50 the pumping action of the cylinders during

admission strokes either alone or in connection with the pumping action of a fan impeller or a supercharger as incorporated in the design of modern air-cooled aero engines. This arrangement not only simplifies the embodiment of my invention but adds another advantage to it, namely: the warm air drawn from the cylinders is thus directed into the carburetor and facilitates the carburetion of the fuel.

For a better understanding of the invention, reference may now be had to the accompanying drawings, forming a part of the specification, of which;

55 Figure 1 is a diagrammatic fragmentary elevational view of an internal combustion engine having a cooling device embodying the invention mounted thereon;

60 Figure 2 is a fragmentary front elevational view of an engine shown by Figure 1;

65 Figure 3 is a fragmentary elevational view of one of the engine cylinders having two suction tubes mounted adjacent thereto;

70 Figure 4 is a fragmentary side-elevational view of an engine having a cooling device mounted thereon; and

75 Figure 5 is a front elevational view of the construction shown by Figure 3.

80 Referring to Figures 1 and 2, a propelled vehicle 10 is shown supporting an internal combustion engine 12, that is provided with air-cooled cylinders 13 arranged radially about a propeller shaft 14. The air strikes the cylinders in a direction indicated by the arrow 15 in Figure 1. A manifold 16, mounted upon the engine, is provided with conduits 17 which are disposed adjacent the rear or leeward portions of the several cylinders and are provided with openings 18.

85 It will be observed that one or more conduits 17 can be located adjacent each cylinder, as shown by Figures 2 and 3. An air intake connection 20 of a conventional carburetor 21 is secured to the manifold 16, and conduit connections 25 also lead from the carburetor to the cylinders 13 for the purpose of transmitting suction forces from the cylinders to the carburetor and thence to the conduits 17.

90 Air is drawn by suction from the leeward

portion of each cylinder by utilizing the suction stroke of the pistons of the engine, or by other suitable means. Since the air that is drawn away from the rear of the cylinders 5 13 and directed into the carburetor 21, is heated by the cylinders, the carburetion of fuel is facilitated and the air-fuel mixture is rendered more favorable for proper combustion in the engine.

10 In Figures 3 and 4 the operation and construction shown is similar to that described above, and since the only material difference is in the construction of the engine wherein the cylinders shown by the later figures are 15 arranged in series, the same numerals are employed to designate similar elements and the same description applies thereto.

Although I have illustrated only the preferred forms of the invention and have described those forms in detail, it will be apparent to those skilled in the art that the invention is not so limited, but that various modifications may be made therein without departing from the spirit of the invention 25 or from the scope of the appended claims.

What I claim is:

1. In an air-cooled engine having a cylinder normally exposed to an air stream, a suction producing means independent of the 30 initiation of said air stream, the suction producing means touching the boundary layer of air adjacent the leeward portion of the cylinder for drawing said boundary layer away from the cylinder.

35 2. In an internal combustion engine having cylinders normally exposed to an air stream, hollow members having openings communicating with the boundary layer of air about the leeward portions of the cylinders, and suction producing means for drawing the boundary layer of air away from the leeward portions of the cylinders through the hollow members.

3. In an air-cooled engine having cylinders 45 normally exposed to an air stream, hollow members having openings disposed adjacent the leeward portions of the cylinders and communicating with the boundary layers of air about the cylinders, a carburetor, a manifold connected to the hollow members and to the carburetor and suction producing means for drawing air from the leeward portions of the cylinders through the manifolds to the carburetor.

55 4. In an air-cooled engine having cylinders normally exposed to an air stream, a manifold having connections communicating with the leeward surface portions of the cylinders, a carburetor having an intake connection 60 and suction producing means for drawing air from the leeward surfaces of the cylinders and directing it to the air intake connection, said suction-producing means including connections to the interior of the cylinders.

5. In an internal combustion engine having a cylinder normally exposed to an air stream, means establishing communication between the interior of the cylinder and the leeward surface thereof for utilizing the suction of the cylinder to draw air from the boundary layer of air about said leeward surface.

6. In an air-cooled engine having cylinders normally exposed to an air stream, hollow members disposed adjacent the leeward portions of the cylinders, and means for utilizing the suction produced in the cylinders for drawing the boundary layer of air away from the surfaces of the cylinders through the hollow members.

In witness whereof, I have hereunto signed my name.

Signed at Akron, in the county of Summit and State of Ohio, U. S. A., this 3d day of September, 1929.

WILHELM FISCHER.
